Primary Examiner — George D. Kirschbaum
Assistant Examiner — Antoinette Martine Suiter

(57) **CLAIM**

The ornamental design for a thermometer, as shown and described.

DESCRIPTION

1. Thermometer
- 1.1 : Perspective
- 1.2 : Perspective
- 1.3 : Front
- 1.4 : Back
- 1.5 : Left
- 1.6 : Right
- 1.7 : Top
- 1.8 : Bottom
- 1.9 : Exploded

The broken lines shown in the drawings are included for the purpose of illustrating portions of the thermometer that form no part of the claimed design.

1 Claim, 9 Drawing Sheets
